X-RAY APPARATUS

Raymond R. Machlett, Riverside, Conn., assignor
to Machlett Laboratories Incorporated, Spring-
dale, Conn., a corporation of Connecticut

Application November 17, 1938, Serial No. 240,965

15 Claims. (Cl. 250—89)

This invention relates to X-ray apparatus of the type adapted for heavy duty use in fine detail radiography and provided with an X-ray tube in which the target surface of the anode is caused 5 to move relatively to the electron stream during operation. More particularly, the invention is concerned with a novel shockproof radiographic apparatus of the type referred to, which is of small size and light weight so that it is easy to 10 handle and may be conveniently installed in existing equipment.

In present radiographic equipment employing rotating anode tubes, the tube ordinarily used contains a rotor cylinder mounted on bearings 5 on a shank sealed through one end of the tube envelope, the cylinder being rotated during operation by the action of the field produced by a stator winding surrounding that portion of the tube containing the cylinder. The anode is 10 mounted on the inner end of the cylinder or forms a part thereof, and its target face is conical or frusto-conical with its axis constituting a prolongation of the axis of the shank. The cathode is mounted at the other end of the envelope and 15 it includes one or more incandescent filaments lying offset from the axis of rotation of the target face and directing an electron stream against the face. In shockproof equipment containing such tubes, the tube lies horizontally in a housing 20 having a window and the position of the tube is such that the useful X-rays leaving the conical surface of the target pass out through the window.

Such equipment as now made is objectionable 25 in that the tubes used are of considerable length, and since they lie horizontally in the housings, the latter have an overall length substantially greater than that of the tubes so that the apparatus is bulky and difficult to manipulate. 10 Also, such prior tubes are expensive to manufacture because of the difficult and laborious operation of accurately grinding the conical or frusto-conical target face of the anode, and the cathode 15 filaments must be exactly placed in the envelope with reference to the target face so that the focal areas will be at the desired locations. The positioning of the target face and cathode relative to one another is particularly difficult in such tubes when two filaments are employed and the 20 operation requires careful and exact workmanship.

The present invention is, accordingly, directed 25 to the provision of a shockproof radiographic device from which the objectionable features of the prior equipment are absent, and the new unit

is light and compact and also of low cost of manufacture. The new device includes an X-ray tube in which the target is a flat disc rotating on the longitudinal axis of the tube, and the use of such a flat disc makes possible important economies 5 both in the production of the target and also in the construction and installation of the cathode. Since the target is flat and the useful X-ray beam must be taken off at a suitable angle to obtain optimum conditions with reference to the focal 10 spot, the tube is mounted within the housing at an angle to the longitudinal axis thereof and with this arrangement, the housing may be supported in the usual way with its longitudinal axis horizontal so that the angular location of the 15 tube does not lead to errors on the part of the operator. The housing which is shockproof and rayproof contains a dielectric fluid in which the tube and its connections are immersed, and since the tube is relatively short and mounted angularly, the overall length of the housing is substantially less than that of housings used in certain prior apparatus.

In addition to those mentioned above, the new apparatus includes numerous other novel features which will be pointed out in the detailed description to follow when considered in connection with the accompanying drawings. In these drawings—

Fig. 1 is a longitudinal sectional view of the 30 new apparatus showing the tube in side elevation;

Figs. 2 and 3 are sectional views on the lines 2—2 and 3—3, respectively, of Fig. 1;

Fig. 4 is a top plan view of the apparatus with 35 parts shown in section;

Figs. 5 and 6 are sectional views taken on the lines 5—5 and 6—6, respectively, of Fig. 4;

Fig. 7 is a longitudinal sectional view of the 40 new tube;

Fig. 8 is a view of the rotor cylinder in side elevation;

Fig. 9 is a sectional view on the line 9—9 of 45 Fig. 8;

Fig. 10 is a longitudinal sectional view through the cathode and a part of the target, the section being taken on the line 10—10 of Fig. 11; and

Fig. 11 is a sectional view on the line 11—11 of 50 Fig. 10.

Referring to the drawings, the apparatus in the form illustrated includes a housing generally designated 20, which is of suitable metal and grounded. The housing preferably consists of an upper part 21 and a removable bottom 22 and the upper part and bottom have peripheral flanges 55

23, 24, respectively, meeting in a horizontal plane. A gasket 25 is interposed between the flanges to make the housing liquid tight and the two parts of the housing are connected together in any suitable way, as by screws 26 threaded through openings in one flange and into the other. The housing is rayproofed by being provided with a lead lining 27 throughout those portions of the two parts of the housing through which X-rays might otherwise pass, and the bottom of the housing is formed with an opening closed by a window 28, which is made of a suitable material, such as a phenolic condensation product. The housing, as illustrated, is symmetrical about a plane normal to the longitudinal axis of the housing and passing through the window, this arrangement facilitating the use of the apparatus.

The window is secured in position in any suitable way, and, for this purpose, may be provided with a flange 28a which is held against a gasket 29 in a channel in the bottom of the housing by means of a threaded ring 30. The inner wall 28b of the window lies at an angle to the longitudinal axis of the housing and parallel to the adjacent portion of the envelope of the tube within the housing so that the X-rays from the tube pass through a layer of dielectric fluid of substantially uniform thickness. Attached to the bottom of the housing in alignment with the window is the usual adapter cone 31.

An X-ray tube which includes an envelope 32 having an enlarged central section 33 and reduced neck portion 34, 35, is mounted in the housing by supporting means secured to the upper part of the housing. At one end, the support comprises a bracket 36 of suitable material, such as a canvas base synthetic resin, which is secured to a metal bracket 37 which is attached to a suitable boss 38 projecting downwardly from the inner wall of the top member of the housing. The free end of the bracket 36 is forked and provided with openings at the end of each leg. The neck 34 of the tube is seated in the bracket against a cushion 39 of suitable material, such as cork, and is held in place by a lashing 40 which may consist of strands of linen cord or the like.

The other end neck 35 of the tube is supported in a bracket 41 which is made of a material similar to that used for the bracket 36 and is supported on lugs 42 projecting inwardly from the inner wall of the upper part of the housing. The bracket 41 is attached to the lugs by screws 43 passing through slots in the bracket and into the lugs so that the vertical position of the bracket 41 may be adjusted as desired. The tube neck 35 is maintained in position within the bracket by means of a crossbar 44, attached to the bracket from beneath, and layers 45 of cushioning material, such as cork, are interposed between the neck 35 and the surfaces of the bracket and crossbar.

Extending rearwardly from the upper part of the housing, near the ends thereof, are integral necks 46, each of which contains an insulating thimble 47. Each insulator is provided with a peripheral flange held against a gasket 48 in a channel at the open end of the neck by a ring 49 threaded into the channel. The end of a high tension cable 50a, 50b enters each insulator through a flared collar 51 held in position by a ring 52 threaded on the end of the neck and having a flange overlying a flange on the collar. The cable 50a contains three conductors 53, the bare ends of which enter sockets in terminals 54 projecting through the end of the insulator 47, and these terminals are connected by wires 55 to

the terminals at the cathode end of the X-ray tube. The cable 50b contains a single conductor, the end of which enters a socket in a terminal 56 which projects through the end of the insulator. A conductor 57 is connected at one end to terminal 56 and has its other end held beneath the head of a screw 58 threaded into a shank 59 which enters the end of the neck 35, and lies with its axis coincident with that of the envelope.

The housing 20 contains a quantity of dielectric liquid, such as oil, in which the tube and its connections are immersed, and to permit expansion of the oil when it is heated during operation, the upper part of the housing is provided with chambers 60 opening into the interior of the housing and containing collapsible bellows 61. Between the chambers 60 is a chamber 62 in the inner wall 63 of which are mounted three terminals 64. Conductors 65 lead from these terminals to terminals in a receptacle 66 mounted in the bottom wall of chamber 62, and current is supplied to the receptacle terminals in the usual way from a three wire cable 67 through the prongs of a plug 68 at the end of the cable. The inner ends of the terminals 64 are connected by suitable conductors (not shown) to windings 69 mounted in slots in a laminated core 10, the windings and core forming a stator through the middle of which extends the neck 35 of the tube. The stator is mounted in position by means of a bracket 71, secured to the top of the core and to a boss 72 projecting downwardly from the inner wall of the upper part of the housing.

The tube envelope 32 consisting of the central enlarged portion 33 and necks 34, 35 is symmetrical about a longitudinal axis passing through the necks, and the necks have re-entrant end portions. The neck 35 is of less diameter and greater length than the neck 34 and the shank 59 entering the neck 35 is sealed to the re-entrant end portion thereof by a tubular metallic seal 73, the shank being provided with a portion 74 of enlarged diameter just inside the seal.

A rotor cylinder 75 of ferromagnetic material is mounted on the portion of the shank 59 within the tube for rotation, and for this purpose, roller bearings are interposed between the cylinder and shank, the bearings being of a suitable alloy which will withstand the degassing treatment necessary. The bearing near the outer end of the cylinder comprises a split inner race 76 through which the shank passes, the race being in contact with the inner face of the enlarged portion 74 of the shank. The balls 77 lie between the inner race and an outer race 78 which is in contact with the inner surface of the cylinder 75, the race being held against outward movement relative to the cylinder by suitable means, such as one or more set screws 79 threaded through the wall of the cylinder. The inner ball bearing also consists of a split inner race 80 in contact with the outer surface of shank 59, balls 81, and an outer race 83 in contact with the inner surface of the cylinder. The inner races of the ball bearings are kept at the proper spacing by a sleeve 84 surrounding the shank, and the outer races are similarly spaced by a sleeve 85 lying against the inner surface of the cylinder. The inner race 80 is held against moving off the end of the shank by the head of a screw 86 threaded into the end of the shank, and the outer race 83 is kept from moving out of the cylinder by a frusto-conical member 87 secured to the end of the cylinder and projecting inwardly to overlie the end of the race.

A hollow stem 88 of a metal of low heat con-

ductivity, such as molybdenum, is secured to the member 87 with its axis forming a prolongation of the axis of the shank 59, and the stem 88 is provided with a peripheral boss 89 having a flange which is preferably interrupted, so that the flange provides a series of lugs. A flat target disc 91 of suitable material, such as tungsten, is mounted on the stem 88 and the flange 90 contacts with one face of the disc. The disc is held in position on the stem by a nut 92 threaded on the end of the stem and the nut preferably has a plurality of spaced lugs 93 engaging the other surface of the disc. By the construction shown, a pathway of low-heat conductivity leads from the disc back to the cylinder so that heat is dissipated from the disc during operation largely by radiation.

During the operation of the tube, the target disc is rotated on the longitudinal axis of the tube by the action of the field produced by the stator 20 on a rotor consisting of the ferromagnetic cylinder 75 and a copper squirrel cage embedded therein. The squirrel cage which is of the same general construction as those used in induction motors, consists of end rings 94 connected by longitudinal bars 95, the metal forming the rings and bars being introduced into suitable channels in the surface of cylinder 75 by vacuum casting. The squirrel cage portion of the rotor structure lies within the stator, as shown in Fig. 7, and a sleeve 30 96 of suitable insulating material is interposed between the stator and the neck 35 of the tube, a layer of cushioning material 97, such as impregnated cambric, being interposed between the sleeve 96 and the tube envelope.

Projecting inwardly through the re-entrant end portion of the neck 34 of the tube is a tube 98 through the outer end of which are sealed the conductors 55. The tube 98 projects into the envelope beyond the re-entrant end portion of the neck 34 and on the inner end of the tube is mounted a slotted metal sleeve 99 which is held in place by circular straps 100. The ground conductor 101 is connected electrically to the sleeve 99.

In the inner end of the sleeve is mounted a block 102 to which is attached an arm 103 and attached to the end of the arm is a block 104 having one or more semi-cylindrical channels 105 in its outer face in which filaments are mounted.

In the construction shown, there are two such filaments 106a, 106b of different lengths and each filament is mounted between two wires 107a, 107b extending through passages in the block 104 and corresponding openings through the arm 103.

One wire 107a for each filament passes through an insulating bushing 108 in the arm 103 and is connected to one of the conductors 55, the portion of the conductor from the bushing to the seal at the end of the tube 98 being provided with insulation. The conductors 55 pass out through an opening in the sleeve 99 and enter a cup 109 attached to the rear face of the arm 103, within which they are connected to the wires 107a. The other wire 107b makes contact with the arm 103 in its opening therethrough and is connected to ground through the arm, the sleeve 99, and the ground conductors 99, 55.

The filaments are in the usual coiled form and lie with their axes parallel to the face of the target disc 91. In order that the electron streams from the two filaments may be directed against the same area on the disc, the inner face of the block 104 is re-entrant and is formed with two plane surfaces lying at an angle to one another. The angle between the surfaces is such that the

electron streams from the filaments are focused by the walls of the semi-cylindrical recesses 105 to strike the same area on the target, as indicated in Fig. 10.

In some instances, it may be desirable to provide a getter within the tube and for this purpose, a conductor 110 may be mounted within the tube 98 and connected to the conductor 99 leading to ground. That portion of the conductor 110 lying within the tube is coated with gettering material 10 and is connected to a conductor 55 sealed through the end of the tube 98 and supplied with current through a suitable connection, not shown.

In prior apparatus provided with an X-ray tube with a rotating target, the target surface has been formed with an inclination to the central ray of the useful beam in order that the elongated focal spot on the target may be foreshortened and produce a substantially square pattern representing a concentrated beam on the object to be radiographed. As the object is ordinarily supported in horizontal position, it has been the practise to mount the anode to rotate on the longitudinal axis of the tube and to support the tube with that axis horizontal. Under those conditions, an inclination of the target surface at an angle of about 15° to the central ray is obtained by forming the surface at an angle of about 75° to the tube axis. The desired foreshortening effect thus depends on accurate formation of the target surface and equally accurate positioning of the cathode filaments with reference to the surface. Similarly, in the case of a two filament tube, the filaments must be accurately mounted in proper angular relation to one another, in order that their focal spots on the inclined target surface will lie parallel and in similar relation to the external object. The difficulties involved in producing target surfaces of tungsten inclined at the necessary angle and in positioning the filaments relative to the surface and to one another add materially to the cost of production of such tubes.

In the present apparatus, the use of the flat target disc affords important economies in cost of manufacture in that the anode may be made more easily and cheaply and the formation of the cathode and the positioning of the filaments relative to the target disc are simple operations and can be done with great accuracy. A flat disc of tungsten may be formed without difficulty and any grinding necessary is carried on in a plane instead of at an angle to an axis. Moreover the filaments may be mounted in the cathode with their axes parallel and the formation of their support to obtain the desired focusing is a relatively simple machining operation.

Another advantage obtained by the use of a flat disc target rotating in a plane at right angles to the tube axis is that the possibility of stray electrons passing from the target face into that part of the tube lying behind the target is greatly reduced. With the target face at an inclination to the axis of rotation, the range of travel of such electrons is much greater than in the case of the flat disc and the danger of injury being done by such electrons is correspondingly increased.

Since the new tube has a flat target lying at right angles to the tube axis and the target surface should be at an angle of from 15° to 25° to the central beam to obtain the desired foreshortening of the focal spot, the tube itself is mounted in the housing at an appropriate angle relative to the longitudinal axis thereof. With this arrangement, the housing may be supported, as is usual,

- with its longitudinal axis horizontal, so that the operator does not have to consider the angular position of the tube to the horizontal. The particular adjustable mounting provided makes it easy to place the tube in correct position, and the angular relation of the tube to the housing makes it possible to make the housing somewhat shorter in overall length than would be possible if the tube axis and that of the housing were parallel.
- 10 In the apparatus described, the housing encloses only the tube and its associated parts but for some purposes, it may be desirable to employ a larger housing containing both the tube and a transformer, and in that case, the tube is again mounted so that the target face makes the desired angle to the central beam. In both constructions, the tube is preferably positioned so that the electron stream from the cathode strikes the target surface on the same side of the axis of rotation as that on which the object to be radio-graphed lies, but the cathode may be placed to provide a focal spot on the other side of the axis, when a longer focal distance is desired.
- I claim:
- 25 1. An X-ray apparatus which comprises a housing having a window, the housing being symmetrical with respect to a transverse plane passing through the window, an X-ray tube within the housing having an envelope containing an anode mounted for rotation relative to the envelope on the longitudinal axis of the tube and having a substantially flat face and a cathode directing an electron stream against said face of the anode at one side of the axis of rotation thereof, and means for supporting the tube within the housing in such position of inclination relative to the longitudinal axis of the housing that X-rays from said face of the anode will pass through the window.
- 30 2. An X-ray apparatus which comprises a ray-proof housing having a window, an X-ray tube within the housing containing a rotary anode having a target face lying substantially in a plane and a cathode directing an electron stream
- 35 against the target face at one side of the axis of rotation thereof, and means for supporting the tube within the housing with the longitudinal axis of the tube inclined to the longitudinal axis of the housing and in such position that X-rays from the target face will pass through the window.
- 40 3. An X-ray apparatus which comprises a housing having a window, an X-ray tube within the housing containing an anode rotatable on the longitudinal axis of the tube and having a substantially flat target face and a cathode directing an electron stream against the target face at one side of the axis of rotation of the anode, and means for supporting the tube within the housing with the plane of rotation of the target face at an oblique angle to the longitudinal axis of the housing and in such position that X-rays therefrom will pass outwardly through the window.
- 45 4. An X-ray apparatus which comprises a housing having a window, the housing being symmetrical with respect to a transverse plane passing through the window, an X-ray tube within the housing having an envelope containing an anode having a flat target face and mounted for rotation relative to the envelope on the longitudinal axis of the tube and a cathode offset from said axis and directing an electron stream against said target face, and means for supporting the tube within the housing in such

position of inclination relative to the longitudinal axis of the housing that X-rays from the target face will pass through the window.

5. An X-ray apparatus which comprises a housing containing a dielectric medium and having a window, an X-ray tube within the housing immersed in the dielectric medium, the tube containing a rotary anode having a substantially flat target face and a cathode directing an electron stream against the target face at one side of the axis of rotation thereof, and means for supporting the tube within the housing with its longitudinal axis at such an oblique angle to the longitudinal axis of the housing that X-rays from the target face will pass through the window, the portion of the window adjacent the surface of the tube lying substantially parallel to that surface.

6. An X-ray apparatus which comprises a housing containing a liquid dielectric medium and provided with a window in one wall thereof, an X-ray tube within the housing lying with its longitudinal axis at an angle to the longitudinal axis of the housing, the tube being immersed in the medium and containing an anode from which X-rays pass out of the housing through the window, and means for supporting the tube within the housing, the portion of the window adjacent the surface of the tube envelope lying spaced a substantially uniform distance therefrom to provide a film of the liquid through which the rays pass which is of substantially uniform thickness.

7. An X-ray apparatus which comprises an elongated housing having an upper part and a removable bottom therefor provided with a window, the upper part and bottom having meeting edges extending lengthwise of the housing, an X-ray tube within the housing, and means for supporting the tube from the upper part of the housing in such position that X-rays from the tube will pass through the window, the tube being exposed from end to end on removal of the bottom of the housing.

8. An X-ray apparatus which comprises a housing having an upper part and a removable bottom therefor provided with a window, an X-ray tube within the housing, the tube containing a rotary anode having a substantially flat target face and a cathode directing an electron stream against the face at one side of the axis of rotation thereof, and means attached to the upper part of the housing for supporting the tube with the flat target face of the anode at such an oblique angle to the longitudinal axis of the housing that X-rays from the target face will pass through the window.

9. An X-ray apparatus which comprises an elongated housing made up of an upper part and a removable bottom provided with a window, the upper part and bottom having meeting edges extending lengthwise of the housing and the latter containing a dielectric liquid, an X-ray tube within the housing and immersed in the liquid, terminals in the wall of the upper part of the housing, connections from the terminals to the terminals of the tube, and means attached to the upper part of the housing for supporting the tube in such position that X-rays therefrom will pass through the window, the tube being exposed from end to end on removal of the bottom of the housing.

10. An X-ray apparatus which comprises an elongated housing made up of an upper part and

a removable bottom provided with a window, the upper part and bottom having meeting edges extending lengthwise of the housing and the latter containing a dielectric liquid, an X-ray tube within the housing and immersed in the liquid, terminals in the wall of the upper part of the housing, connections from the terminals to the terminals of the tube, collapsible means secured to the upper part of the housing and permitting expansion of the liquid as the latter is heated, and means attached to the upper part of the housing for supporting the tube in such position that X-rays therefrom will pass through the window, the tube being exposed from end to end on removal of the bottom of the housing.

11. An X-ray apparatus which comprises an elongated housing made up of an upper part and a removable bottom provided with a window, the upper part and bottom extending from end to end of the housing, an X-ray tube within the housing, the tube containing a rotatable anode and a cathode, a stator winding on the tube at the anode end, means secured to the upper part of the housing for supporting the stator winding, and means secured to the upper part of the housing and engaging the tube adjacent the ends thereof for supporting the tube, the removal of the bottom exposing the tube from end to end.

12. An X-ray apparatus which comprises a housing made up of an upper part and a removable bottom provided with a window, the upper part and bottom extending from end to end of the housing, an X-ray tube within the housing, the tube containing a rotatable anode having a substantially flat target face and a cathode for directing an electron stream against the target face at one side of the axis of rotation of the anode, and means secured to the upper part of the housing for supporting the tube with its longitudinal axis inclined to the horizontal, the cathode end of the tube being lower than the anode end and projecting into the bottom of the housing.

13. An X-ray apparatus which comprises a housing having a window in one wall thereof, an X-ray tube within the housing, the tube containing an anode rotatable on the longitudinal axis of the tube and provided with a substantially flat target face and a cathode eccentric to said axis and directing an electron stream against the target face at one side of the axis of rotation thereof, and means for supporting the tube within the housing with its longitudinal axis at an oblique angle to the longitudinal axis of the housing such that X-rays from the target face pass through the window.

14. An X-ray apparatus which comprises a housing having a window in one wall thereof, an X-ray tube within the housing, the tube containing a rotatable anode having a substantially flat target face and a cathode directing an electron stream against the target face at one side of the axis of rotation of the anode, and means for supporting the tube within the housing in such an inclined position relative to the longitudinal axis of the housing that the electron stream from the cathode strikes the target face below the axis of rotation of the anode and X-rays from the target face pass through the window.

15. An X-ray apparatus which comprises a housing elongated along one axis and having a window in one lateral wall thereof, an X-ray tube within the housing containing an anode mounted for rotation and having a substantially flat target surface lying at right angles to the axis of rotation of the anode, and a cathode for directing an electron stream against the target surface at one side of the axis of rotation of the anode, and means for supporting the tube within the housing in such position of inclination relative to said axis of the housing that the plane of the target surface makes a relatively small angle with the central ray of the X-ray beam leaving through the window in a direction normal to said axis of the housing.

RAYMOND R. MACHLETT.
